United States Patent Office

Des. 227,023
Patented May 29, 1973

227,023

TOY CONSTRUCTION PIECE OR SIMILAR ARTICLE

Raymond W. Baker, 596 Bishop Ave.,
Bridgeport, Conn. 06610

Filed Sept. 30, 1970, Ser. No. 25,274

Term of patent 14 years

Int. Cl. D21—01; D18—03
U.S. Cl. D34—15 GG

Fig. 1

Fig. 3.

Fig. 2.

Fig. 4.

FIG. 1 is a perspective view of a toy construction piece or similar article, showing my new design;

FIG. 2 is a front elevational view, the rear being substantially a mirror image thereof;

FIG. 3 is a top plan view, the bottom being substantially a mirror image thereof; and

FIG. 4 is a side elevational view, the opposite side being substantially a mirror image thereof.

We claim:

The ornamental design for a toy construction piece or similar article, substantially as shown and described.
